COIN BANK

Frank W. Bower, Goshen, Ind.

Application June 4, 1954, Serial No. 434,458

5 Claims. (Cl. 232—5)

The present invention relates to coin banks and, particularly, to a device in the form of an attachment adapted to be secured to a conventional container to comprise a coin bank.

A coin bank to be truly practical must provide a receptacle, a coin slot through which coins may be inserted into the receptacle, a one-way valve structure or the like at the slot whereby coins inserted in the receptacle cannot be removed from the receptacle through the slot, and a locking arrangement whereby the coins cannot be removed from the receptacle except by authorized persons. While the receptacle may take various forms, the provision of a coin bank receptacle constitutes a large cost factor due to the necessity for special formation and manufacture of the receptacle. In addition, a preference has been acquired in the art for transparent receptacles or containers since the same accommodate ready observation of the coins accumulated and saved. Obviously, the provision of a specially formed, high grade, transparent receptacle is very costly.

In my copending application, Serial No. 353,037, filed May 5, 1953, Pat. No. 2,709,037 I have disclosed an improved coin bank comprising a coin receptacle in the form of a conventional milk bottle and a coin bank cover attachment for the bottle. By utilizing a conventional bottle that is mass produced at a very low cost, I am able to afford a high grade transparent receptacle in a very economical and practical manner. The cover attachment is readily locked to the container and a coin slot is provided therein, a one-way valve being associated with the slot to accommodate insertion and prevent removal of coins through the slot. Thus, an attractive coin bank of a truly practical nature as above defined is afforded very economically.

Broadly, the objects of the present invention are to afford an improved coin bank including a conventional container as a coin receptacle and to provide an improved coin bank cover attachment for conventional containers.

In respect of the cover attachment of the present invention, it is to be observed that heretofore cover attachments for various items have comprised a pair of cover parts hingedly connected at one side thereof and including latch or lock means at the opposite side thereof. In my aforesaid copending application, I have disclosed a coin bank attachment cover for milk bottles including a pair of semi-circular parts having an articulated joint at the periphery thereof on one side of the cover and cooperating eye means at the diametrically opposed side of the cover.

It is an object of the present invention to afford an improved coin bank cover attachment for conventional containers incorporating an improved, simplified and more economical arrangement for securing the two parts together in locked relation on the container.

In accordance with the immediately foregoing object, I provide a coin bank cover attachment comprising a pair of preferably complementary parts adapted to be joined together to complement and close the opening in a con-

2

tainer, each of the parts including at the peripheral or outer edge thereof downwardly and inwardly curved fingers or tabs adapted to grasp and interlock with the lip surrounding the opening in the container. At the line of separation between the two parts, each part includes an upstanding tab disposed generally transversely of the line of separation, the two tabs being disposed immediately adjacent one another and having aligned bores therein for the passage of the bolt of a lock. Upon attachment of the parts to a container, and passage of the lock bolt through the aligned bores or holes in the upstanding tabs, the two parts become fixed together and locked to the container. The upstanding tabs and/or the mating edges of the two parts prevent relative rotation and longitudinal movement transversely of the line of separation of the two parts in the plane of the lip of the receptacle or container, and the depending fingers engaging the lip of the container prevent separation of the two parts from the container in a direction along the line of separation of the parts and in planes at right angles to the plane of the lip. Accordingly, the present invention, while affording as firmly locked an attachment or cover as any prior art endeavor, greatly simplifies and effects substantial economies in the attachment and locking of the cover parts together.

Further according to the invention, the structure is preferably simplified and made as economical as possible by forming the two cover parts identical to one another, each of the parts comprising, preferably, a unitary metallic stamping including the finger and tab portions which are, subsequently, curved downwardly and inwardly and bent upwardly, respectively. At least one of the two parts is provided with a coin slot therein, and a simple but highly practical one-way valve is secured to the lower surface of one of the parts to afford valve means intersecting the slot when the attachment is applied to a receptacle or container.

With respect to the improved coin bank of the invention, I fabricate the improved cover attachment above described to accommodate attachment of the same to the opening and lip of a conventional, preferably transparent container, in particular, a fish bowl. As will be apparent, the continuous mass production of fish bowls by a number of manufacturers leads to a very low priced receptacle, particularly as compared to the necessity for providing specially formed containers in conventional coin banks. The coin bank of the invention is preferably supplied to the user as a complete bank including the fish bowl receptacle, the cover attachment and a lock. The resultant bank is economical, highly practical and very attractive, and provides all the advantages that coin banks should possess.

From the foregoing, it is to be appreciated that the present invention affords a highly improved and practical coin bank cover attachment for conventional containers, and an improved coin bank, both of which are afforded at the greatest economy possible.

Other objects and advantages of the present invention will become apparent in the following detailed description of a preferred embodiment of the invention.

Now, in order to acquaint those skilled in the art with the manner of constructing and using the coin bank means of the invention, I shall describe, in connection with the accompanying drawing, a preferred embodiment of the invention and one manner of making the same.

In the drawings:

Figure 1 is a perspective view of the coin bank of the invention comprising a conventional fish bowl and the cover attachment of the invention applied thereto;

Figure 2 is a plan view of the two parts of the cover attachment of the invention as completely formed and properly associated with one another;

Figure 3 is a plan view of the basic stamping defining each part; and

Figure 4 is a fragmentary sectional view, on a reduced scale, showing the association of the receptacle lip and the fingers of the coin bank cover attachment.

Referring now to the drawings, I have shown in Figure 1 the bank of the present invention as comprising a conventional fish bowl 10, serving as a transparent coin receptacle, and a cover attachment, indicated generally at 12, for the bowl, the attachment providing a coin slot 14 leading to the interior of the receptacle and being adapted to be secured to the receptacle or bowl by means of a lock 16.

The cover attachment 12 is shown in Figure 2 as comprising a pair of cover parts 18 and 20. Since the opening, or open end, of a fish bowl is usually elliptical, the cover parts 18 and 20 are each preferably generally semi-elliptical. However, it will be appreciated as the description proceeds that the cover parts may take other forms as required to conform to various shaped openings. The cover parts 18 and 20 may be formed in any suitable manner, but the same preferably comprise metal stampings originally formed flat as shown in Figure 3 and then formed, in a manner to be described, to the form shown in Figure 2. As shown in Figure 3, each of the parts 18 and 20, as originally stamped flat from sheet stock, includes at the outer or peripheral edge thereof, a plurality of outwardly extending finger or tab portions 22. Each of the fingers 22 is adapted to be rolled downwardly adjacent the base of the finger so that the fingers extend downwardly or depend from the plate portions of the parts 18 and 20. Also, the fingers 22 are rolled inwardly adjacent the lower end thereof so as to present a generally convex outer surface as the same are viewed in side elevation. As shown in Figure 4, the curvature of the finger or tab portions 22 provides an interfitting engagement with the lip 24 surrounding the top or open end of the fish bowl 10, whereby the cover parts may be secured to the bowl with the fingers 22 grasping and interlocking with the lip 24 and holding the cover to the bowl.

Along the mating edges of the two parts 18 and 20, that is at the inner edge thereof, each of the parts is preferably cut in such manner that the edges of the two parts mate with and complement one another. Preferably, the inner edge is so cut as to accommodate formation of a tab, to be disposed generally transversely of the line of separation of the two parts, integral with each part. In the preferred embodiment, this is accomplished by means of an edge configuration including a generally convex edge portion 26 along about one-half of the cover part, a generally concave edge portion 28 along about the other half of the cover part and undercut with respect to the edge portion 26, and a straight edge portion 30 extending generally transversely of and joining the edge portions 26 and 28, preferably along the longitudinal axis of the cover part. By undercutting the portion 28 with respect to the portion 26, adequate space is provided for the formation of a tab 32 integral with the cover part and projecting preferably perpendicularly from the edge portion 30. Other edge configurations will suggest themselves to those acquainted in the art and modifications of the edge configuration are to be expected within the scope of the invention. Also, separate formation and attachment of the tab to the cover plate is an obvious modification. In a simple form, the inner edge of each part could be straight, and a tab could be separately secured to the part to extend transversely of and preferably intersect the line of separation of the two parts. However, the preferred structure is as shown and described, wherein the inner edges are of irregular configuration and the tab is formed integral with the cover part to extend transversely of and intersect the general line of separation of the two parts.

By forming the inner edge and the tab in the manner shown and described, a minimum of material is required for the stamping of complete cover parts from sheet

metal. Also, the disposition of the edge portion 30 along the axis of the parts, transversely of the line of separation of the parts, accommodates the association of two identical parts in the manner shown in Figure 2, whereby a minimum of dies and material are required in the manufacture of the attachment. Preferably, in the initial stamping operation, a hole 34 is formed in the tab 32. Thereafter, the coin slot 14 is formed, preferably in the central portion of the plate, in alternate parts, as is indicated in dotted lines in Figure 3.

After two cover parts have been formed flat in the manner described, with the coin slot 14 in one of the two, the tab 32 of each part is bent to one side of the plate, upwardly, to extend perpendicularly of the plate, the line of bending being indicated by dotted line in Figure 3. The fingers 22 are each curved to the opposite side of the plate, downwardly, and inwardly to accommodate the grasping and interfitting relationship with the lip 24 of the bowl as shown in Figure 4. The two cover parts are then mounted on the bowl 10 in the manner shown in Figures 1 and 2, with each part closing half of the opening in the bowl or container and with the fingers thereof grasping the lip surrounding or encompassing the opening. The adjacent edges of the two parts, as described above, mate with and complement one another, with the convex portion 26 of each part mating with and in the concave portion 28 of the other part, and with the two tabs 32 disposed immediately adjacent one another, preferably in abutting or substantially abutting relationship, with the holes 34 therein aligned. When the bolt 36 of the lock 16 is passed through the aligned apertures or holes 34, the coin bank cover attachment becomes locked to the fish bowl container or receptacle 10. Due to the bolt 36, the two parts cannot be separated longitudinally, that is, at right angles to the line of separation of the two parts, and the fingers 22 grasp the bowl to prevent raising of the parts. Relative movement of the two parts along the line of separation is prevented by the fingers 22 and the abutting relationship of the upstanding tabs 32 and/or the edges 30 of the two parts. Relative rotation of the parts 18 and 20 is likewise prevented by the abutting relationship of the tabs 32 and/or the complementary mating edges of the two parts. This relationship, which assures retention of the coin bank cover attachment on the container, is existent in all forms of the cover irrespective of the size or configuration of the container and cover. The tabs 32 preferably extend generally transversely of the line of separation of the parts to assure substantial elimination of relative movement of the parts transversely of the line of separation, and are preferably located at or adjacent the center of the cover to insure prevention of relative rotation or pivoting of the parts. To disassociate the cover attachment from the container, the lock is removed and the parts 18 and 20 simply slid away from one another.

To complete the bank, a one-way valve 38, preferably of thin section spring metal, is attached, as by a rivet 40, or in any other customary manner, to the lower surface of the cover part (18) having the coin slot 14 therein. The valve 38 includes a plurality of resilient fingers 42 which intersect and span the slot 14, the fingers 42 being flexibly bendable to accommodate insertion of coins into the container through the slot, and normally resiliently engaging the lower surface of the cover part to prevent removal of coins from the fish bowl container through the slot.

From the foregoing, it will be appreciated that the present invention affords a highly desirable and attractive coin bank, having all the merits a coin bank should possess, in a very economical and convenient manner. The transparent receptacle, comprising preferably a mass produced fish bowl of good quality, is provided at a minimum cost. The cover attachment of the invention readily and conveniently imparts all of the essential requirements of a coin bank to the fish bowl. The at-

tachment itself is very economical of manufacture and incorporates improved lock means of a high practical and very economical nature that insures firm securement of the attachment to the bowl.

While I have described what I regard to be a preferred embodiment of my invention, it will be apparent that various changes, rearrangements and modifications may be made therein without departing from the scope of the invention, as defined by the appended claims.

I claim:

1. A coin bank cover attachment for receptacles comprising a pair of cover parts, each of said parts including means at the outer edge thereof to grasp the receptacle, a tab on each of said parts adjacent the line of separation of said parts, said tabs extending upwardly from said cover parts and having aligned holes therein, and a lock bolt to extend through the aligned holes in said tabs, said tabs and said lock bolt constituting the sole means of connecting said parts.

2. A coin bank cover attachment for receptacles comprising a pair of cover parts, each of said parts including finger means at the outer edge thereof to grasp the receptacle, said cover parts at the inner edges thereof including complementary edge portions mating with one another along the line of separation of said parts, an upstanding tab on each of said parts adjacent the center of the inner edge thereof, said tabs extending generally transversely of and intersecting the general line of separation of said parts, said tabs being disposed immediately adjacent one another and having aligned holes therein longitudinally of the line of separation of said parts, a lock bolt to extend through the aligned holes in said tabs, said tabs and said lock bolt constituting the sole means of connecting said parts, said tabs, said complementary edge portions of said parts and said finger means preventing removal of said parts from the receptacle upon insertion of said lock bolt in said holes, and a coin slot in at least one of said parts.

3. A coin bank cover attachment for receptacles comprising a pair of substantially identical cover parts which together complement the opening in the receptacle to close the opening, each of said parts including downwardly and inwardly curved fingers at the outer edge thereof to grasp the receptacle about the opening therein, said cover parts at the inner edges thereof including complementary edge portions, said portions including a convex edge portion extending to approximately the center of the cover part, a concave edge portion extending the remainder of the distance across the cover part and undercut with respect to said convex edge portion, and a straight edge portion joining the convex and concave edge portions, a single tab formed integrally with each of said cover parts along the straight edge portion thereof, said tabs extending upwardly from said cover parts im-

mediately adjacent one another and having aligned holes therein longitudinally of the general line of separation of said parts, a single lock bolt to extend through the aligned holes in said tabs, said two tabs and said single

5 lock bolt constituting the sole connection between said parts, said tabs and complementary edge portions of said parts upon insertion of said lock bolt preventing relative rotation of said parts and relative movement of said parts transversely of the line of separation thereof, said fingers 10 preventing raising of said parts from the receptacle and relative movement of said parts along the line of separation thereof, and a coin slot in one of said parts.

4. A coin bank comprising a receptacle having an opening therein and a lip encompassing said opening, and a 15 coin bank cover attachment for said receptacle, said attachment comprising a pair of cover parts which together complement and close said opening, said parts each including at the outer edges thereof downwardly and inwardly curved fingers grasping and interlocking with said lip, said cover parts at the inner edges thereof each including a single upstanding tab, said tabs having aligned holes therein, and a lock bolt extending through said holes, said tabs and said lock bolt comprising the sole means of connection of said cover parts and together 20 with said fingers preventing relative movement of said parts and preventing removal of said parts from said bowl, and a coin slot in at least one of said parts.

5. A coin bank comprising a fish bowl having an opening therein and a lip encompassing said opening, and a 25 coin bank cover attachment for said fish bowl, said attachment comprising a pair of cover parts each including at the outer edge thereof downwardly and inwardly curved fingers grasping and interlocking with said lip, said cover parts at the inner edges thereof including complementary 30 edge portions, a single upstanding tab on each of said cover parts, each of said tabs being located substantially centrally of the inner edge of the respective parts and extending transversely of said inner edge, said parts complementing and closing the opening in said bowl, said tabs substantially abutting one another and having aligned holes therein, a lock having a bolt extended through said holes, said tabs and said lock constituting the sole means 35 of connecting said parts, said tabs, said lock and said fingers preventing relative movement of said parts and removal of said parts from said bowl except upon removal of said lock from said tabs, and a coin slot in one 40 of said parts.
